SHEET METAL CONTAINER WITH PLASTIC
CLOSURE

John A. Foster, Rockford, Ill., assignor to J. L. Clark
Manufacturing Co., Rockford, Ill., a corporation of
Illinois

Filed Sept. 2, 1965, Ser. No. 489,787
13 Claims. (Cl. 220—60)

This application is a continuation-in-part-of my co-pending applications Ser. Nos. 338,397, filed Jan. 17, 1964, now abandoned, and 425,470, filed Jan. 14, 1965, now abandoned.

The invention relates to a container of the type in which a skirt depending from the periphery of a cover of flexible plastic is telescoped with the end of a tubular sheet metal body and interlocked beneath a downwardly facing shoulder to fasten the cover securely to the body.

The general object is to form a container of the above character in which the resiliency of the plastic of the cover is utilized in a novel manner to secure the cover to the shoulder which is formed by bending a narrow portion of the metal at the end of the tubular body laterally and then reversely to form an end lip of curved cross-section terminating at the metal edge which forms the shoulder.

Another object is to interlock the cover skirt and the edge of the metal shoulder in a novel manner not only to fasten the cover securely to the metal body but also to form a tight seal all around the resulting joint.

A more detailed object is to maintain the interlocked relation through a novel coaction between the cover skirt and a second depending skirt concentric with the main skirt and engaging the body end on the opposite side of the lip thereof.

A further object is to effect tight sealing of the cover on the body by wedging the body lip into a downwardly opening groove defined by the opposed surfaces of the two skirts.

Another object is to shape the shoulder engaging surface of the cover skirt in a novel manner to insure tight and uniform sealing in spite of dimensional variations in the cover and body resulting from manufacture of the cover and body by modern high production plastic molding and metal forming machinery.

The invention also resides in the manner of achieving the foregoing objects by forming the body lip as a relatively flat hem.

Other objects and advantages of the invention will become apparent from the following detailed description taken in connection with the accompanying drawings, in which

FIGURE 1 is a perspective view of a plastic covered sheet metal container embodying the novel features of the present invention.

FIG. 2 is a perspective view of one end of the container body.

FIGS. 3 and 4 are enlarged fragmentary sections taken along the lines 3—3 and 4—4 of FIGS. 1 and 2 respectively.

FIGS. 5 and 6 are similar cross-sections illustrating steps in the shaping of the container body.

FIGS. 7 and 8 are views similar to FIGS. 1 and 2 showing on a ten size scale a preferred form of the invention.

FIGS. 9 and 10 are fragmentary cross-sections taken along the lines 9—9 and 10—10 of FIGS. 7 and 8 respectively.

FIG. 11 is a fragmentary section of the plastic cover taken along the line 11—11 of FIG. 7.

FIG. 12 is a fragmentary section taken along the line 12—12 of FIG. 7 in the course of assembly of the cover and container body.

2

FIG. 13 is a fragmentary cross-sectional view similar to FIG. 11 showing a modified construction of the skirt on the plastic cover, the parts being shown as ten times actual size.

FIG. 14 is a fragmentary sectional view taken along the line 14—14 of FIG. 13.

FIG. 15 is a fragmentary perspective view of a part of FIG. 14.

FIGS. 16 and 17 are sectional views similar to FIG. 9 showing the modified cover as assembled on the container body when the parts of the cover and body are of the intended dimensions, the sections being taken respectively along the lines 16—16 and 17—17 of FIG. 14.

In the container shown in FIGS. 1 to 3 of the drawings, a generally rectangular cover 10 composed of yieldable plastic material such as polyethylene or a combination of polyethylene and polypropylene is formed with a depending peripheral skirt 11 telescoped snugly down over the end of a tubular body 12 and interlocked with a downwardly facing peripheral shoulder 13 thereon to fasten the cover securely on the body. The body, which may be of any desired cross-sectional shape, is formed from a rectangular blank of sheet metal in a standard high speed body maker and therefore has an interlock and flattened seam 15 extending along one side over nearly the full length of the body. One or more parts of the cover are adapted to be raised to expose an opening through which the container contents may be removed or dispensed.

In accordance with the present invention and in the form shown in FIGS. 1 to 6, the cover is fastened on the end of the tubular body by interengagement of the shoulder 13 and an interned peripheral bead 16 integral with the lower edge portion of the skirt 11 and in the final assembly disposed below the shoulder, an edge 18 thereof in effect biting into the softer plastic surface 19 of the bead. Such secure interengagement of the plastic and the metal is achieved by a novel construction of the shoulder 13 and a laterally opening peripheral recess 17 disposed immediately below the shoulder and formed in an automatic sequence along with the conventional body making steps above described. For this purpose, the shoulder is eventually a raw metal edge of the original metal blank whose one edge portion is converted, by well known bending technique, into a partial curl or, in the present instance, into a hem 21, the fold 22 of which curl or hem defines the end or lip of the final tubular body. Thus, the edge portion of the blank, in the case of the preferred hem construction, is bent outwardly and then reversely substantially against the body as shown in FIG. 5 so as to leave the hem relatively flat with the edge 13 thereof spaced from the fold 22 a distance somewhat less than the spacing between the upper side 19 of the bead 16 and a surface 23 on the under side of the cover around the upper end of the skirt 11. Preferably, a narrow space 24 on the order of .004—.006 of an inch is left between the two parts 25 and 26 that form the hem 21.

The width and radial depth of the peripheral groove 17 corresponds to that of the bead 16 as shown in FIG. 3. It is disposed in a position such that the raw edge 18 of the shoulder 13 is well exposed and adapted to bite into the softer plastic of the bead on the upper side 19 thereof and thus increase the gripping action which holds the skirt securely interlocked with the end of the body.

The groove 17 is formed in a final station of the body forming machine after completion of the hemming, tubing, and seaming operations to convert the sheet metal blank into the form shown in FIG. 2. This is accomplished by the coaction of expandable inner and outer dies 27 and 28 (FIGS. 5 and 6) which are duplicated around the body and arranged for engagement with the full periphery of the can body. With the parts at rest in the positions

shown in FIG. 5, the outer dies 28 are then collapsed inwardly thus stretching this metal inwardly beyond the hem shoulder to form the groove 17 to the desired depth when the dies reach the positions shown in FIG. 6. In this operation, the hem is engaged and bent inwardly somewhat by a surface 29 on the outer die leaving the outer surface of the hem diverging somewhat downwardly at a small angle and also offset inwardly as determined by the position of the inner die surface 31.

With the upper edge 32 of the laterally opening groove 17 disposed substantially at or above the shoulder 13, the edge 18 of the hem is exposed for certain engagement with the upper portion 19 of the bead 16 in spite of the relative flatness and thinness of the hem. In view of the yieldable character of the plastic of the bead, the shoulder or edge 18 of the hem will bite or sink somewhat into the plastic and thus lock the bead and skirt effectually against outward movement. Such secure fastening is achieved automatically as an incident to placing the skirt 11 of the cover in alignment with the lip 22 of the body and pressing the cover downwardly until the top of the cover becomes substantially seated on the lip. In such telescoping, the lip of the body encounters the inwardly and upwardly converging surface 33 around the lower edge of the bead and cams the bead outwardly so as to allow the hem to pass. Then, as the hem edge 18 reaches the outwardly and upwardly diverging upper surface 19 of the bead, the skirt contracts and the bead snaps in beneath and into biting engagement with the hem edge as the flange 25 of the hem comes opposite the wall 34.

In the final assembly shown in FIG. 3, the closed end of the hem fits closely in a downwardly opening groove defined by the wall 34 of the skirt 11 and an opposed substantially parallel wall 35 of a second and shorter inner skirt 36 integral with and depending from the cover 10 concentric with the outer skirt 11. Below the wall 35, the outer surface 37 of the inner skirt converges downwardly from an upper radius about equal to the internal radius of the bead 16. Thus, in the telescoping operation and after the hem lip 22 passes the bead, it engages the surface 37 which acts in the continued downward movement of the cover to guide the hem into its final position within the groove 34, 35. In this position, the outer surface of the skirt 11 is substantially flush with the outer surface of the body 12 by virtue of the offsetting of the hem inwardly from the latter surface at the bend 38.

A modified form of the invention is shown in FIGS. 7 to 11 in which the major parts are indicated by the same but primed reference numerals. In this instance, the shoulder 18' on the hem 21' is disposed on the inside of the body 12' and accordingly the long and short skirts 11' and 36' are respectively disposed inside and outside of the body hem 21'. The bead 16' is formed around the interior of the longer skirt 11' and its upper surface 43, which is engaged by the hem edge 18' in the final assembly, is wider horizontally than the thickness of the hem edge 13', is substantially flat in radial cross-section, and converges downwardly and outwardly at an angle of about 45 degrees. With this substantial inclination of the surface 43 relative to the horizontal, the inner skirt 11' will strip properly off from that portion of the die which forms the groove 34', 35' between the skirts 11' and 36' in the molding operation.

The thickness a of the hem is about .023 of an inch which is about three times the thickness (about .008 of an inch) of the metal 25', 26' forming the hem, these parts being disposed substantially parallel in the present instance. The recess 17' for effecting exposure of the hem edge 18' opens inwardly in this instance and is defined by an offset 49 which begins at a point 42 somewhat above the hem edge and diverges downwardly parallel to the upper surface 43 of the bead 16' and finally merges with the inner side wall 41 of the body 12'. The downwardly opening groove which is defined by the skirt surfaces 34', 35' is disposed in vertical alignment with the

top surface 43 of the bead. The vertical width of the hem is correlated with the depth of this groove so that in the final assembly, the hem edge 18' engages the inner edge portion of the surface 43 as shown in FIG. 9.

5 To insure tight sealing between the cover and the hem, the hem and skirts are dimensioned to provide for wedging or pinching of the closed end portion of the hem in between the opposed walls 34', 35' of the groove defined thereby with the lip 22' of the hem disposed somewhat short of the bottom 23' of the groove. For this purpose, these walls converge slightly upwardly and toward each other and, at the points 47, 48 of engagement with the closed end portion of the hem, are spaced somewhat closer together as indicated at b (FIG. 11) than the radial thickness a (FIG. 10) of this portion of the hem, the difference being a few thousandths of an inch. Thus, the second skirt 36' serves not only as a lateral backing for maintaining the body lip 22' positioned properly relative to the skirt 11' and the bead 16' but also coacts with the latter in providing two effective seals at 47 and 48 near the lip of the container and all around the sides of this lip in spite of dimensional variations that may occur in high production manufacture of the engaging portions of the metal and plastic.

25 As before, the lower surface 44 of the bead 16' is inclined at a substantial angle and positioned for engagement with the lip 22' of the hem as the cover is pressed onto the hemmed end of the body. The angle of inward convergence is about 60 degrees in the present instance.

30 Thus, as the cover is pressed onto the hem 21', the lip 22' engages the surface 44 and bends the skirt 16' inwardly as shown in FIG. 11. Before the hem edge passes the surface 44, the lip 22 encounters and rides along the downwardly diverging surface 45 of the outer skirt and into the groove between the walls 34', 35'. In the continued movement and as the hem edge is presented to the upper bead surface 43, the skirt 11' expands moving the bead surface 43 outwardly beneath the hem edge 13'. Downward pressure on the cover is continued until the lip 22' of the hem becomes fully seated and wedged in between the walls 34', 35' during which the skirt continues to expand moving the bead surface 43 farther across the hem edge (FIG. 9). The parts are dimensional so that the final engagement between the hem edge 18' and the bead is intermediate the edges of the surface 43, this position varying somewhat with dimensional variations in the interengaging parts. Thus, the bead always interlocks effectually with the exposed hem edge 18' so as to hold the cover securely on the container body with opposite sides of the hem sealed tightly against the surfaces 34', 35' of the outer and inner skirts 36' and 11'.

55 In the high production manufacture of the plastic and metal parts of the above character, there may be dimensional variations of sufficient magnitude to prevent attainment of the desired uniform sealing pressure between the hem and the opposed surfaces of the cover skirts of all containers. To compensate automatically for such variations and always insure optimum sealing of the cover around the body lip, the invention, in another of its aspects, contemplates a modification of the contour of the downwardly diverging surface 43 of the bead 16' as shown in FIGS. 13 to 17 so that the edge 18' of the shoulder 13' engages the bead 16' only at points spaced around the top surface of the bead thus allowing the hem edge 13' to penetrate the top of the bead to different depths at these points after the hem lip 22 has become seated and properly wedged in between the skirt surfaces 34', 35'.

60 In the present instance such points of engagement between the hem edge and the bead are defined by nibs 51 molded integral with and upstanding from the bead surface 43. Herein, the nibs take the form of ribs upstanding from and extending across the full radial width of the bead surface 43. All are of substantially the same cross-section with opposite sides 52 diverging from the upper-

65 70 75

most edge 54 toward the bead surface 43 to offer different degrees of resistance to penetration by the hem edge 18' in the final assembled position of the cover on the container body. Herein and as shown in FIGS. 14, 15, the ribs are of generally rounded cross-section, for example one-eighth inch radius, are about one-eighth of an inch wide and .010 of an inch high, and are inclined at about 45 degrees relative to the horizontal. The spacing of the ribs along the bead may vary to suit the possible dimensional variations of the parts or the characteristic of the plastic being used. For example, in a two or four ounce spice can as shown in FIG. 7, it is preferred to provide three or four of the ribs 51 along the sides of the cover, these being spaced equidistantly apart with the terminal ribs similarly spaced from the corners of the cover. Two similarly spaced ribs are provided along the bead 16' at the ends of the cover. By virtue of such spacing, the part of the molding die by which the groove between the skirts is made thinner only at the ribs is not weakened materially by the presence of the ribs.

In pressing the cover shown in FIGS. 13 and 14 onto the hemmed end of the body 12', the lip 22' cams the skirt 16' outwardly until the outer ends 53 of the ribs 51 pass the hem edge 18'. Then the skirt begins to contract and, in the continued movement of the cover, the ribs move outwardly and in beneath the edge until the lip has become wedged into the groove and pressed into sealing contact with the skirt surfaces 34', 35'. At this time, the movement of the ribs across the edge 18' is interrupted and the edge bites into the top of the ribs to a depth determined by the relative axial dimensions of the hem and cover groove and also by the relative radial dimensions. Thus, when the cover and hem are of the intended dimensions, the edge 18' will engage and penetrate the ribs as shown in FIG. 16. Between the ribs, the edge 18' will normally be spaced above the bead surface 43 as shown in FIG. 17.

Now, if the hem is abnormally deep or the groove 34', 35', shallower than intended, the ribs will move a lesser distance inwardly by the time the lip 22' becomes seated. Conversely, if the hem is short or the cover groove is long, the skirt 16' will expand a greater distance and in the final assembly, the edge 18' will engage farther up on the ribs. In all cases within the normal variations attainable in the manufacture of such parts, it has been found that the hem edge always engages the rib surfaces properly while the lip 22' is wedged into the cover groove under sufficient pressure to provide effective seals around the entire periphery of the cover.

It will be apparent from the foregoing that the second depending skirt 36 (FIGS. 1 to 3) or 36' (FIGS. 8 to 17) performs several important functions. First, it forms a lateral backing which acts to hold the hem in proper position relative to the skirt 11' and thus insuring that the hem edge 18' will remain properly interlocked and in biting engagement with the bead 16'. Secondly, its surface 34' coats with the surface 35' of the inner skirt 11' to provide for wedging and pressure seating of the hem against two opposed surfaces 34', 35'. Sealing pressure of substantial magnitude around the two surfaces is facilitated by making the hem of substantial depth so that the sealing and wedging is effected at surfaces which are formed by the upper and less flexible end portions of the two skirts. In addition, by employing a relatively flat hem instead of a wide curl, manufacture of the container is simplified and location of the outer plastic and metal surfaces substantially flush with each other is facilitated.

I claim as my invention:

1. A container having, in combination, a body comprising a sheet metal tube, a cover of resilient plastic substantially abutting one end of the tube and having a preformed laterally flexible depending peripheral skirt telescoped with the end portion of said tube, and means securing the cover and tube together comprising a pre-

formed relatively flat metal hem at said tube end including a peripheral flange bent laterally and then reversely to project along and lie closely adjacent one side surface of the tube and terminating in an edge spaced longitudinally from the tube end, the portion of said body below said hem being offset radially from said hem so as to expose the hem edge and thus increase the effective width of the shoulder formed thereby and facing longitudinally of the tube, a bead integral with said skirt adjacent the lower edge thereof and level with said offset portion and urged, by virtue of the resiliency of said skirt, laterally across said hem edge and toward said offset portion, said bead having an upper frusto-conical surface engaging and interlocking with said exposed hem edge, and a second peripheral skirt shorter than said first skirt depending from said cover on the side of the hem opposite said first skirt and engaging the closed end portion of the hem to hold the hem edge in permanent biting engagement with said bead surface.

2. A container having, in combination, a body comprising a resilient sheet metal tube, a cover of resilient plastic substantially abutting one end of the tube and having a preformed laterally flexible depending peripheral skirt telescoped with said tube end, and means securing said cover onto the tube end comprising an end portion of said tube bent laterally and then reversely to define a lip of curved cross-section terminating in an axially facing shoulder spaced longitudinally from said lip and providing an exposed sharp cornered edge, a bead integral with said skirt adjacent the lower edge thereof and urged laterally across and beneath said shoulder by virtue of the relative resiliency of said skirt and said lip, said bead having an upwardly facing and downwardly inclined frusto-conical surface engaging said sharp edge with the latter digging into and interlocking with the softer plastic of said surface, and a peripherally continuous second skirt depending from said cover and laterally spaced from said first skirt to engage the end of said tube and hold said edge in permanent biting engagement with the upwardly facing surface of said bead, the opposed surfaces of said two skirts above said bead forming a downwardly opening groove into which said lip of said body is seated.

3. A container as defined in claim 2 in which said second skirt is axially shorter than said first skirt.

4. A container as defined in claim 2 in which a portion of said tube below said shoulder is offset radially at the same level as said bead to dispose the remaining lower surface of the tube substantially flush with the external surface of the outer one of said skirts.

5. A container as defined in claim 2 in which said shoulder is the edge of a relatively flat hem which is substantially wider than it is thick.

6. A container as defined in claim 5 in which the spacing of said shoulder from said lip is several times the thickness of the lip.

7. A container as defined in claim 5 in which the wall of said tube opposite said bead is offset radially away from said shoulder to increase the exposure of said shoulder for biting engagement with the upper side of said bead.

8. A container as defined in claim 7 in which said wall offset starts at a point above said shoulder and slopes downwardly away from said bead.

9. A container having, in combination, a body comprising a resilient sheet metal tube, a cover of resilient plastic substantially abutting one end of the tube and having a preformed laterally flexible depending peripheral skirt telescoped with said tube end, and means securing said cover onto the tube end comprising an end portion of said tube bent laterally and then reversely to define a lip of curved cross-section terminating in an axially facing shoulder spaced longitudinally from said lip and providing an exposed sharp cornered edge, a bead integral with said skirt adjacent the lower edge thereof and urged laterally

across and beneath said shoulder by virtue of the relative resiliency of said skirt and said lip, said bead having an upwardly facing and downwardly inclined frusto-conical surface engaging said sharp edge with the latter digging into and interlocking with the softer plastic of said surface, and a peripherally continuous second skirt depending from said cover and laterally spaced from said first skirt to engage the end of said tube and hold said edge in permanent biting engagement with the upwardly facing surface of said bead, the opposed surfaces of said two skirts above said bead forming a downwardly opening groove into which said lip of said body is seated, the opposed surfaces of said two skirts above said bead converging upwardly and pinching said lip between them at points spaced from the upper closed end of the groove to provide tight seals around the tube end on the inner and outer sides thereof.

10. A container having, in combination, a body comprising a sheet metal tube, a cover of resilient plastic substantially abutting one end of the tube and having a laterally flexible depending peripheral skirt telescoped with said tube end, and means securing said cover onto the tube end comprising an end portion of said tube bent laterally and then reversely to define a lip of curved cross-section terminating in an edge spaced longitudinally from said lip and providing an exposed inwardly and axially facing shoulder, a bead integral with said skirt adjacent the lower edge thereof urged laterally across said shoulder by virtue of the resiliency of said skirt, a plurality of ribs by standing and extending across the top of said bead at points spaced around the periphery of said skirt, the upper edges of said ribs being inclined downwardly from said skirt to the free edge of said bead so as to engage said shoulder and hold the intervening portions of the shoulder out of engagement with said bead, and a second skirt depending from said cover and engaging the side of said

5 tube end opposite said first skirt to hold said shoulder in permanent engagement with said rib edges.

11. A container as defined in claim 10 in which the surfaces of opposite sides of each of said ribs diverge downwardly toward the top surface of said bead whereby to allow for different degrees of penetration of said shoulder in the different ribs.

10 12. A container having, in combination, a body comprising a sheet metal tube having an end portion bent laterally and then reversely to form a lip of arcuate cross-section at the end of the tube and a downwardly facing shoulder spaced longitudinally from said lip, a cover of resilient plastic material having two laterally spaced and flexible skirts depending therefrom and defining between them a peripheral and downwardly opening groove receiving said lip with the lip wedged in between the opposed surfaces of said skirts, a bead integral with one of said skirts and underlying said shoulder, and a plurality of ribs integral with and upstanding from the upper side 15 of said bead and permanently engaging said shoulder to hold said lip wedged into said groove.

13. A container as defined in claim 12 in which each 20 of said ribs comprises a rib having downwardly diverging sides and inclined downwardly and across said bead for engagement with said shoulder at different points along 25 its top edge depending on dimensional variations in said groove and the spacing of said shoulder from said lip.
